UNITED STATES PATENT OFFICE.

CORNELIUS DE VOS, OF IOWA CITY, IOWA.

PRINTER'S LEAD AND SLUG RACK.

SPECIFICATION forming part of Letters Patent No. 250,215, dated November 29, 1881.

Application filed August 4, 1881. (No model.)

To all whom it may concern:

Be it known that I, CORNELIUS DE VOS, of 5
Iowa City, in the county of Johnson and State
of Iowa, have invented an Improved Printer's
Lead and Slug Rack, of which the following
is a specification.

The object of my invention is to save time
and labor in using and taking care of print-
ers' leads and slugs.

10 It consists in forming a neat, strong, and
durable rack in such a manner that it will
have series of graduated spaces with bottoms
inclining backward and also laterally, into
which different sizes of leads and slugs can be
15 readily placed, so that they will incline inward
to prevent them from falling out, and also in-
cline against each other to be retained in their
respective places, from whence they can be con-
veniently lifted out and used, all as hereinafter
20 fully set forth.

Figure 1 of my drawings is a perspective
view of my improved rack. Fig. 2 is a trans-
verse section. Together they clearly illustrate
the construction and operation of my complete
25 invention.

20 A are the upright end pieces of my rack-
frame, preferably made of wood, and tapering
on the front edge. They are rigidly connected
by means of a narrow top piece, B, and a wide
30 base-piece, C, being fastened on their ends
with nails, screws, or in any suitable way. The
top ends of the end pieces shown are only three-
fourths of an inch wide and the bottom ends
35 four and one-half inches; but they may vary
in size as desired to produce complete racks
of different sizes.

D is an upright partition, corresponding in
form and size with the end pieces, A. 1 2 3
represent a series of horizontal partitions, that
40 divide the complete rack into series of grad-
uated spaces or shelves adapted to receive
and retain leads and slugs of different sizes.
These partitions are made of thin wood, paper-

board, sheet metal, or other suitable material,
and fastened into grooves formed in the up- 45
right pieces A D, or rigidly fixed thereto in any
suitable way, so that they will form a grad-
uated series of shelves that incline from the
front and open side of the rack rearward, and
also from one end of the rack toward the other. 50
The incline from the open front to the rear
and closed back, E, is three-sixteenths of an
inch or more, and the incline from end to end
is no less than about one inch.

Figures indicating the sizes of the shelves or 55
spaces are fixed upon the front edges of the
upright pieces A D, to aid the operator in plac-
ing leads and slugs of different sizes in their
respective places.

I am aware that cases, galleys, and racks of 60
various forms, having spaces of different sizes,
have been used for keeping assorted sizes of
types, slugs, and leads. A lead-rack having
its top and bottom tapering to produce shelves
and compartments differing in depth, and there- 65
by adapted for leads graduated in length, has
also been used; but my rack, having shelves
graduated in depth and inclining laterally and
also rearward, and adapted to receive assorted
70 sizes of slugs and leads placed in standing po-
sitions on their edges, to be retained station-
ary in such standing positions by means of the
doubly-inclined shelves and their own force of
gravity, is novel and greatly advantageous.

I claim —

75 As an improved article of manufacture, a
printer's lead and slug rack having series of
graduated shelves 1 2 3, that incline from the
front to the rear and from one end toward the
other, substantially as shown and described, 80
for the purposes specified.

CORNELIUS DE VOS.
